EDGAR C. LACKLAND, OF NEW HAVEN, CONNECTICUT, ASSIGNOR TO ROCKBESTOS PRODUCTS CORPORATION, OF NEW HAVEN, CONNECTICUT.

ELECTRICAL HEATER ELEMENT.

Application filed May 7, 1924. Serial No. 711,568.

This invention relates generally to the construction of heater elements for use in electrical heating devices.

In the manufacture of electrical heating pads in the prior art it has been the practice to wind a bare conductor on a flexible support of insulating material and to arrange the element thus produced in a convoluted formation in order to obtain the necessary 10 length of resistance wire in a given space, and then to enclose the heater element between pads of material having a suitable insulating quality. It has been known also to wind the resistance wire together with a 15 yarn formed of cotton or other suitable material and to place this element within the heating pad to be formed. It has been found that the heating element formed in the latter manner is open to the objection that a 20 sharp bend produced in the element tends to force the resistance wire out of its protective position in contact with the yarn so that the wire is then exposed and does not move back into its protective position when the bend 25 is removed from the conductor. This gives rise to a possibility of short circuiting the conductor or of setting fire to the material forming the pad. In either type of construction referred to the insulation is not 30 satisfactory and leads to the making of an inferior product.

It is an object of the present invention to provide a heater element for the general purpose referred to which will be free from 35 these objections and in addition will be inexpensive to manufacture and will provide in other ways an article superior to the article produced in prior methods of manufacture.

40 The invention includes the production of a heater element which forms either the weft or the warp element of a loosely woven fabric, the heater element consisting of a resistance wire so wound or wrapped in a 45 specially formed asbestos roving that the wire is permanently situated at substantially the axial center of the insulating winding or casing provided. By this construction a heater element is formed in which no 50 amount of bending can force the wire from its protected position at the center of the insulating casing. The other element of the weave, that is, the warp or weft yarn is formed by a yarn produced by twisting as 55 bestos roving threads of the same type used

in insulating the resistance wire so that an effective means for holding the various stretches of the heater element in a suitably spaced apart insulated relation is provided.

Not only is an effective insulation thus 60 provided for the heater element but the use of resistance wire in the form of an element of the woven fabric produces a relatively pliable structure which particularly facilitates the use of the heater element in heating 65 pads such as are used for therapeutic purposes. The fabric formed in this manner is preferably of an open mesh character which, as will be seen, adds to the pliability desired and also enhanced the insulating 70 qualities of the structure.

It is possible to produce a multiple heating effect by the use of two resistance wires woven together in the fabric from the same shuttle. Preferably in such a case the two 75 elements would be colored differently so as to distinguish them apart in the assembly of the device.

In the drawings, in which a preferred embodiment of the invention has been selected for illustration,

Figure 1 is a view in a more or less diagrammatic form of a heater element made in accordance with the invention,

Figure 2 is a view on an enlarged scale of 85 a resistance wire element used in the production of the device shown in Figure 1.

Figure 3 is a view similar to Figure 1 showing a modified form of the invention.

Referring to the drawings for a more detailed description of the invention, Figure 1 shows an open mesh fabric formed with a weft thread 10 consisting of a suitably insulated resistance wire and of a series of warp threads 11 formed of insulating material similar to and substantially the same size as is provided by the weft thread element 10. It will be noted that the fabric thus formed is of an open mesh character and is correspondingly pliable. A heater 100 element of this type is easily stitched into place between the soft flannel covering members such as are used in electrical heating pads of this general construction.

The heater element 10 is constructed as 105 shown in Figure 2 of the drawing and consists of a length of resistance wire 12 which may be formed of nichrome or other material suitable for the purpose and insulated by a winding formed of asbestos 13 preliminarily 110

wound on a reinforcing or carrier thread 14 and then wound in relatively close coils on the wire 12. By this structural arrangement a yarn is formed having excellent heating and electrical insulating qualities of asbestos fibers and with the tensile strength provided by the reinforcing thread which makes it possible to produce the relatively close winding desired. With this arrangement the wire is retained in its position at the center of the insulating mass and does not protrude or break through the insulation when the fabric is sharply bent.

The warp threads 11 of the structure are preferably formed of yarn members formed of the same material used in insulating the resistance wire. Preferably two thread reinforcing asbestos rovings are twisted together to form a yarn. In a preferred construction of the heater element two rovings of this character are used in providing the insulating winding for the wire so that the warp elements and the weft element are of the same general character and diameter thereby forming a fabric of a uniform character. It will be seen that the fabric thus formed has an open mesh formation, the effect of which is to produce a relatively spaced apart relation between the stretches of the weft element 10 forming the heater element. In this way a doubly effective insulation of the weft element stretches from each other is obtained.

In a modified form of the invention shown in Figure 3 of the drawing a double heater element 10 is provided formed of a pair of resistance wires wound as in Figure 2 and woven into the fabric from the same shuttle reel. Preferably the two elements are colored differently or otherwise distinguished to permit of an identification in forming the connections to the source of current. This arrangement provides a combination of heating values since the separate resistance wires

have different resistance capacities thereby providing a combination of three heat producing values.

While I have described my invention with particular reference to a heating pad, it will be readily understood that the same is not limited thereto but may be used in various other electrical heater devices in which the characteristics of the invention may be useful, and thus while I have described a preferred embodiment of my invention, it will be readily understood that the same is not to be limited to all the details shown but is capable of modification and variation within the spirit of the invention and the scope of the appended claims.

What I claim is:—

1. A heating element for electrical heater devices comprising an open mesh woven fabric in which one element comprises a resistance wire having an insulating casing consisting of thread reinforced asbestos rovings helically wound about the wire, and the other elements comprise yarns formed of asbestos rovings twisted together.

2. A heating element for electrical heater devices comprising an open mesh woven fabric in which one element comprises a resistance wire having an insulating casing consisting of asbestos rovings helically wound about the wire, and the other elements comprise yarns formed of thread reinforced asbestos rovings twisted together.

3. A heating element for electrical heater devices comprising an open mesh woven fabric in which the weft element comprises a resistance wire having an insulating casing consisting of thread reinforced asbestos rovings helically wound about the wire, and the warp elements comprise yarns formed of thread reinforced asbestos rovings twisted together.

EDGAR C. LACKLAND.
